(57) **CLAIM**

The ornamental design for a T-shirt, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a T-shirt showing my new design;

FIG. 2 is a rear view thereof;

FIG. 3 is a left side view thereof;

FIG. 4 is a top view thereof;

FIG. 5 is a bottom view thereof;

FIG. 6 is an enlarged view of the image shown in sections A and B of FIG. 1; and

FIG. 7 is an enlarged view of the image shown in sections A' and B' of FIG. 2.

The broken lines on the outer edges of FIGS. 6 and 7 represent an unclaimed boundary
